UNITED STATES PATENT OFFICE.

FREDERICK POPE, OF NEW YORK, N. Y., AND GEORGE M. POPE, OF MOUNT PLEASANT, GEORGIA; SAID GEORGE M. POPE ASSIGNOR TO ELLA M. POPE, OF BOSTON, MASSACHUSETTS.

APPARATUS AND METHOD FOR DISTILLING WOOD.

1,030,011.

Specification of Letters Patent. Patented June 18, 1912.

Application filed June 1, 1910. Serial No. 564,344.

To all whom it may concern:

Be it known that we, FREDERICK POPE, a resident of New York, in the county of New York and State of New York, and GEORGE M. POPE, a resident of Mount Pleasant, in the county of Wayne, State of Georgia, have invented a new and useful Improvement in Apparatus and Methods for Distilling Wood, of which the following is a specification.

This invention relates to apparatus and method for distilling wood, and more particularly for distilling coniferous wood such as pine wood, for the purpose of extracting therefrom spirits of turpentine, pine oil, pitch and other valuable products.

The general object of the invention is to provide for circulating a hot bath over the wood and by means of which the products may be distilled from the wood in greater quantities, in less time, with less waste, and at a less cost than with prior methods and apparatus, and without injury to the fiber or structure of the wood.

The specific object of the invention is to provide apparatus and a method whereby loss of heat is prevented, whereby the solution of the desired products in the bath is largely prevented, and whereby such products as are dissolved in the bath are distilled therefrom as soon as possible, thereby reducing waste.

Generally stated, the invention requires a retort for the reception of the wood to be treated with a bath provided with perforated steam pipes placed above the level of the top of the wood to be treated, and with an outlet for the bath some distance above the level of the steam pipes, together with the necessary heating and circulating apparatus, and a condenser connected to the retort, all as will hereinafter be more fully described and claimed.

In the accompanying drawing Figure 1 is a diagrammatic view partly in section representing the apparatus for carrying out the method; Fig. 2 is a longitudinal section of the retort.

The principal new part of the apparatus is the retort 1 which may be constructed of any suitable material, such as cast or boiler iron or concrete and in any suitable way; the drawing not showing any details of con-

struction. The retort is preferably of considerable length as compared with its width, 55 and is arranged to receive the wood to be treated in cars which are run into and out of the retort through openings closed by doors 3. It is provided with one or more inlets 4 for the bath at its bottom; with one 60 or more outlets 5 for the bath at its upper part; with one or more condenser connections 6 and outlets for the desired products at its top, or at least above the outlets for the bath. Under each of the condenser outlets 6 is a baffle plate 7 to prevent any spray or fine particles of the bath being carried into the condenser by the vapor coming from the bath. It is also provided with perforated steam pipes 8 placed above the 70 level of the top of the wood in the retort, the perforations in which open upwardly so that the escaping steam assists in producing an upward circulation in the retort.

In conjunction with the retort described 75 are the necessary heating, storing and circulating means for the bath, which, however, may be similar to ones now in use. As shown, the overflow pipe 5 leads from the retort to a storage tank 9. From the 80 storage tank a pipe 10 leads to the pump 11, and from the pump the pipe 12 leads to the heating coil 13 in a suitable furnace 14, and thence pipes 15 and 16 lead to the inlet 4 of the retort. A valve 17 is provided in the 85 pipe 16 and a by-pass pipe 18 provided with a valve 19 connects the pipe 15 directly with the storage tank. A drainage pipe 20 provided with a valve 21 connects the bottom 90 of the retort with the storage tank. The outlets 6 are connected to a condenser or condensers 22. One or more heaters, storage tanks, pumps and condensers may be used in connection with one retort. The condenser is preferably connected with an 95 air pump 23 or some other means for maintaining a partial vacuum in the condenser and retort. A grate 24 or other means is supplied for providing the heat in furnace 14.

In carrying out the method described the operation of the apparatus illustrated is as follows: Cars loaded with the wood to be treated are run into the retort 1, and the doors 3 tightly closed. The pitch or other 105 bath is in the tank 9 in a molten condition,

the furnace 14 is heated by a fire on the grate 24 and the pump 11 started. This starts the bath circulating through the apparatus. At this time the valves 19 and 21 are closed and the valve 17 is open. The hot bath circulated by the pump fills the retort submerging the wood until it reaches the outlet opening 5 and then it flows back into the storage tank 9. As the hot bath passes over the wood, the desired products are extracted, or distilled by heat from the wood, some of them passing up through the bath as vapor and through the outlet 6 to the condenser and some of them entering into solution in the bath. These products which have become dissolved in the bath are distilled therefrom by the action of the steam introduced through the perforated pipes 8 and the heat from the bath, as soon as they are above the level of the steam pipes. The bath returns to the storage tank 9 and immediately goes into circulation again. After the wood has been subjected to the action of the bath for the necessary length of time, the valve 19 is opened, valve 17 closed and valve 21 opened. The pump continues in operation but the circulation is now from the storage tank through the pump, through the heater and through pipes 15 and 18 to the storage tank, and the bath in the retort is drained out through drainage pipe 20. The purpose of this circulation is to maintain the temperature of the bath while the charge of wood in the retort is being renewed. When the bath has been entirely drained from the retort the cars containing the wood are run out and cars with a fresh supply of wood are run in and the foregoing operation is repeated. The retort 1 therefore serves a double purpose; the desired products being driven out or extracted from the wood in the lower part of said retort, in a homogeneous hot bath, and the products so derived from the wood are distilled from the bath in the upper part of said chamber, by a pure steam distillation method.

The great advantage of this form of apparatus is that it provides means by which wood may be subjected to a true distilling action by a homogeneous hot bath, so arranged that only a small amount of the products will enter into solution in the bath and so that such products as do enter into solution in the bath shall remain in solution for the smallest length of time possible. Furthermore, this apparatus makes possible the recovery of the maximum amount of products from the wood without resorting to the use of pressure. The steam does not come into contact with the wood, being prevented from doing so by the upward movement of the bath in the retort and the natural tendency of steam to rise, and, further, by the fact that the steam es-

caping from the perforated steam-pipes with considerable velocity is directed upwardly.

What we claim is:

1. Apparatus for obtaining products from wood, comprising a vessel for holding the wood to be treated with a bath, provided with an inlet for the bath at the bottom, an outlet for the bath near the top, and an outlet for the products above the outlet for the bath, and perforated steam pipes located in said vessel above the level of the wood and below the level of the bath therein with the perforations arranged to direct the steam upwardly, whereby all currents in the vessel are upwardly. 70 7b 80

2. Apparatus for obtaining products from wood, comprising a vessel for holding the wood to be treated with a bath, provided with an inlet for the bath at the bottom, an outlet for the bath near the top, and an outlet for the products above the outlet for the bath, perforated steam pipes located in said vessel above the level of the wood and below the level of the bath therein, and circulating and heating means for the bath. 85 90

3. Apparatus for obtaining products from wood, comprising a vessel for holding the wood to be treated with a bath, provided with an inlet for the bath at the bottom, an outlet for the bath near the top, and an outlet for the products above the outlet for the bath, perforated steam pipes located in said vessel above the level of the wood and below the level of the bath therein with the perforations arranged to direct the steam upwardly, whereby all currents in the vessel are upwardly, and circulating and heating means for the bath. 95 100 105

4. Apparatus for obtaining products from wood, comprising a vessel for holding the wood to be treated with a bath, provided with an inlet for the bath at the bottom, an outlet for the bath near the top, and an outlet for the products above the outlet for the bath, perforated steam pipes located in said vessel above the level of the wood and below the level of the bath therein, connections and means for circulating the bath from the outlet of said vessel to the inlet thereto, and means in said circulating connections for heating the bath. 110 115

5. Apparatus for obtaining products from wood, comprising a vessel for holding the wood to be treated with a bath, provided with an inlet for the bath at the bottom, an outlet for the bath near the top, and an outlet for the products above the outlet for the bath, perforated steam pipes located in said vessel above the level of the wood and below the level of the bath therein, a condenser connected to the outlet for the products, and an exhaust connected to said condenser. 120 125 130

6. The method of distilling wood consisting in placing the wood in a closed vessel, circulating a hot bath through the vessel and over the wood from the bottom up-
5 wardly, thereby distilling the desired products from the wood, introducing steam into the bath above the level of the wood and thereby distilling off therefrom such of the products as have become dissolved
10 therein, and drawing the products out of the retort and into a condenser by suction.

In testimony whereof, we have hereunto set our hands.
